UNITED STATES PATENT OFFICE.

FREDERICK HACHMANN, OF ST. LOUIS, MISSOURI, ASSIGNOR, BY DIRECT AND MESNE ASSIGNMENTS, OF FOUR-TENTHS TO HENRY C. SICKMANN, OF MARTHASVILLE, MISSOURI, AND TWO-TENTHS TO CLARENCE S. SIEGFRIED, OF ST. LOUIS, MISSOURI.

COMBINED RAIL JOINT, TIE PLATE, AND ANTICREEPER.

Application filed May 29, 1922. Serial No. 564,575.

To all whom it may concern:

Be it known that I, FREDERICK HACHMANN, a citizen of the United States, and resident of the city of St. Louis and State of Missouri, have invented certain new and useful Improvements in Combined Rail Joints, Tie Plates, and Anticreepers, of which the following is a specification, containing a full, clear, and exact description, 10 reference being had to the accompanying drawings, forming a part hereof.

My invention relates to certain new and useful improvements in combined rail joints, tie plates, and anti-creepers, and has 15 for its primary object a rail joint which also serves the purpose of a tie plate and anti-creeper.

A still further object is to construct a combined rail joint, tie plate, and anti-creeper, in which no bolts are necessary in 20 order to secure the meeting ends of rails together.

This device is an improvement over the device filed jointly by myself and Henry C. 25 Sickmann, January 30, 1922, Serial No. 532,668.

In the drawings,

Fig. 1 is a top plan view of my device.

Fig. 2 is a side elevation of the same.

Fig. 3 is a top plan view of the base.

Fig. 4 is a cross section taken on the line 4—4 of Fig. 1.

Fig. 5 is a longitudinal section with parts broken away, taken on the line 5—5 of Fig. 1.

Fig. 6 is a cross section taken on the line 6—6 of Fig. 1.

Fig. 7 is a cross section of the base taken on the line 7—7 of Fig. 3.

Fig. 8 is a longitudinal sectional view of 40 the resilient locking means as prepared for insertion.

Fig. 9 is a face view of the locking key.

Fig. 10 is a vertical section taken on the line 10—10 of Fig. 9.

45 In the construction of my device, I employ a base 11. This base is provided with wedge seats 12 and 13. Formed integral with the wedge seats, and extending inwardly toward the center of the base 11 are walls 14. These walls are arranged diagonally to the rail, so that the wedges 15 can be inserted. These wedges are tapered both laterally and longitudinally, the larger end being provided with integrally formed up-

wardly extending projections 16. Each projection is provided with a pocket or bore 17. The rear end of this bore is provided with a horizontally extending recess 18. The purpose of the bore 17 and recess 18 will be explained in detail later.

Formed integral with the base 11, and adjacent the wedge bases 12 are formed outwardly extending portions 19. These are provided with an opening so as to form a pocket 20 into which the portion 21 of the locking key 22 extends. This locking key is provided with an opening 23, and in this opening is adapted to be seated the boss 24 of the washer 25. This washer is provided with an outwardly extending flange 26, 70 against which one end of a coil spring 27 rests. The opposite end of the coil spring 27 rests against the flange 28 formed integral with the washer 29. The washer 29 is also provided with a pair of rearwardly extending portions 30, which fit into the recess 18 and prevent the washer 29 from turning. The washer 25 is provided with a cylindrical opening 31 to allow free passage of the bolt 32, while the washer 29 is provided with 80 a screw-threaded bore 33, which receives the threaded end of the bolt 32. The purpose of this bolt is to compress the spring 27, as illustrated in Fig. 8, so as to permit its insertion within the recess 17 sufficiently 85 deep to allow the locking key 22 to be placed in position, after which the bolt 32 is removed and the portion 24 of the washer 25 enters the opening 32, thus securely locking the key in position, and when the bolt is re- 90 moved entirely, a rearward thrust is imparted to the wedges 15. The base 11 is also provided adjacent the wedge seats 13 with an inwardly extending lug 33^a, which with the projection 19 forms a guide for the base 95 flange 34 of the rail. This rail is provided with the usual ball 35, and with the web 36. Located on either side of the rail is a fish plate 40. This fish plate is provided with elongated openings 41, and with an undercut 100 wall 42. Against the undercut wall, one edge of the wedges 15 contacts, and due to the longitudinal taper of the wedges, these fish plates are tightly forced against the rail. The web 36 is provided with a cylindrical opening 43, through which pins 44 extend. These pins are designed to take the place of 105 the usual bolts and are placed in position,

as illustrated in Fig. 6 before the wedges 15 are secured. The wedges 15 when in place, cover the portion of the openings 41 in the fish plates, and thus prevent the pins 44 from 5 coming out. The object of elongating the openings 41 is to permit expansion and contraction of the rails, due to climatic changes. Formed integral with the underside of the base are ribs 45. These ribs are designed 10 to contact with ties 46, and thus prevent creeping of the tie plate, which in turn, by means of the pins 44 prevents creeping of the rails.

In this manner I eliminate the use of rail 15 anti-creepers, thereby saving considerable cost in track construction and maintenance.

The upper face of the base 11 is provided with ribs or pads 47, on which the base flanges 34 rest, and in order to stiffen the 20 base 11, I provide longitudinally extending ribs 48. These ribs extend from one of the wedge bases 12 to one of the wedge bases 13. I have also provided laterally extending ribs 49, which strengthen the ribs 48, and 25 the ribs 50 which strengthen the inclined walls 14.

The installation of my device is as follows:

The base 11 is first placed on ties 46; the 30 rails then placed in position, the projections 19 and 33^a locating the rail in its proper place. The fish plates 40 are then placed on either side of the rail. Here the projections 19 and 33^a come into service again in preventing the fish plates from shifting out of the base, inasmuch as the bases of the fish plates are of such width that they contact with the inside faces of these projections. After the fish plates have been placed in position, the pins 44 are then inserted. The 40 wedges 15 are placed in position, after which the resilient locking means is properly secured in each of the recesses 17. The locking keys 22 are then dropped into position 45 in the pockets 20. The bolt 32 is then removed entirely. This allows the projection 34 to seat itself in the opening 23, while the flange 26 binds tightly against the locking key. The spring exerts a pressure on both 50 the key and wedge, and tends to drive the wedge in tightly, so that any vibration or jarring will seat the wedges still more tightly. After the rails have been thus joined and secured within the base, the 55 track is lined up, after which the ties 46 are brought in contact with the anti-creepers 45, formed on the underside of the base, and the base then secured to the ties by spiking.

60 By the use of my device it is not necessary to have section hands walking along the track continually tightening up bolts which are bound to stretch and jar loose, due to the continual passage of the trains. Furthermore, the rails are held rigid at their meet-

ing ends, which prevents pounding down or flattening of the ends, but insures a smooth riding rail at all times.

It will also be noted from Fig. 5 that the wedges 15 are made hollow with ribs for 70 stiffening purposes. The purpose of this is to reduce the weight of the joint, while at the same time strength is not seriously sacrificed.

Having fully described my invention, 75 what I claim is:

1. A combined rail joint, tie plate, and anti-creep, comprising a base, spaced apart wedge bases formed integral therewith at each end of said base, inclined walls 80 formed integral with said wedge bases, fish plates having undercut surfaces adapted to be seated on either side of the rail, wedges adapted to be inserted between the inclined walls of the wedge bases and undercut surfaces of the fish plates for locking said fish plates against the rail, a pocket formed in said base adjacent each end, a key adapted to be inserted in said pocket, and a resilient locking means adapted to contact with said 90 key and with said wedges for holding the wedges and key in position.

2. A combined rail joint, tie plate, and anti-creep, comprising a base, spaced apart wedge bases formed integral with said base 95 adjacent the longitudinal edges thereof, inclined walls formed integral with said wedge bases and projecting thereover, fish plates having inclined walls adapted to be inserted between the wedge bases, means formed integral with said base for preventing the shifting of said fish plates, wedges having a pocket formed in one end adapted to be seated on said wedge bases and between the inclined walls thereof and said fish plates, a 100 pocket formed at each end of said base, a key having an opening located in each pocket, a coil spring having a washer at each end adapted to be seated in said pocket, one of said washers adapted to enter said key for 110 holding it within the pocket, and means for compressing said coil spring to permit the removal of said key.

3. The combined rail joint, tie plate, and anti-creep of claim 1, in which the base is 115 provided with downwardly projecting ribs, the ribs designed to contact with railroad ties to prevent creeping.

4. The device of claim 2, in which the underside of the base is provided with downwardly projecting ribs which are adapted to contact with railroad ties, and act as an anti-creep. 120

5. A combined rail joint, tie plate, and anti-creep, comprising a base having anti-creeping ribs on its bottom, wedge bases formed integral with said base and located on the top thereof, inclined walls formed integral with said wedge bases, fish plates having inclined walls adapted to be inserted 125 130

between said wedge bases, wedges adapted to be inserted between the fish plates and inclined walls, and resilient means for holding said wedges in position.

5. 6. A combined rail joint, tie plate, and anti-creeper, comprising a base having integrally formed wedge bases projecting therefrom, upwardly and inwardly inclined walls formed integral with each of said wedge bases, fish plates having inclined walls located between said wedge bases, wedges having a bore for securing means, a pocket formed adjacent each end of said base, a key located in each pocket, a spring located in the wedge bore, and means carried by the spring for imparting pressure against the wedges and holding the keys in position.
- 10
- 15

7. The device of claim 6, in which the base is provided with downwardly projecting ribs which are adapted to contact and bear against railroad ties to prevent the creeping of the base thereof.
- 20

8. A combined rail joint, tie plate, and anti-creeper, comprising a base having integrally formed wedge bases projecting therefrom, upwardly and inwardly inclined walls formed integral with each of said wedge bases, fish plates having inclined walls located between said wedge bases, wedges having bores for securing means, a pocket formed adjacent each end of said base, a key located on each pocket, a spring located in the wedge bore, means carried by the spring for imparting pressure against the wedges and holding the keys in position, 35 said tie plates having elongated openings which register with the openings in the web of a rail, and pins located in said openings to limit the longitudinal movement of the rails.

In testimony whereof, I have signed my name to this specification.

FREDERICK HACHMANN.
